UNITED STATES PATENT OFFICE.

WILLIAM WRIGHT VINCENT, OF KENOSHA, WISCONSIN, ASSIGNOR TO THE SIMMONS MANUFACTURING COMPANY, OF KENOSHA, WISCONSIN, A CORPORATION OF WISCONSIN.

LACQUERING-MACHINE.

1,080,392.

Specification of Letters Patent.

Patented Dec. 2, 1913.

Application filed January 4, 1909. Serial No. 470,651.

To all whom it may concern:

Be it known that I, WILLIAM W. VINCENT, a citizen of the United States, residing at Kenosha, in the county of Kenosha and State of Wisconsin, have invented certain new and useful Improvements in Lacquering-Machines, of which the following is a specification.

Devices or machines for the carrying out of the process of lacquering bedsteads set out in my Patent No. 908,911, granted January 5, 1909, form the subject matter of this present application.

One of the objects of the invention is the provision of an appliance capable of holding and supporting the parts of brass bedsteads or other tarnishable pieces during the application of the lacquer thereto, the tubes or other parts of the bedstead being heated by electricity during the coating operation. Preferably means are provided for rotating or revolving the tube or other part being operated upon to bring all the portions or surfaces thereof into position for the application of the lacquer by the operator. This turning may be done either manually or by power, as desired. The holders for the burnished tubes are desirably made tapered, whereby to secure an effective electrical contact between them and the tube or mount, and in some forms I provide such holders or centers with small extensions or pins adapted to temporarily support a polished tube or trimming during the adjustment of one or more of the holders to the piece to be lacquered or its removal therefrom. In addition, suitable means are supplied to send a heating current of electricity through the holders and tube or mount, an electric switch or rheostat being provided for the control of the current. The tail stock is preferably slideable toward and from the head stock so as to adapt the machine for use with tubes of different lengths, and in such tail stock I yieldingly mount the holder so that the tube or bedstead trimming will be held between the pair of holders by spring pressure. Means are also provided for locking the tail stock against backward movement, as otherwise the spring under compression would have a tendency to shift the same rearwardly, relieving the necessary or desired pressure of the holders on the tube.

In the accompanying drawings I have

shown a preferred embodiment of the invention, and in these drawings Figure 1 is a perspective view of the machine; Fig. 2 is a fragmentary back view of the device, certain parts being shown in section; Fig. 3 is a plan view of the construction shown in Fig. 2; Fig. 4 is a fragmentary end elevation of the appliance; Fig. 5 is a section on line 5—5 of Fig. 4, the parts being viewed in the direction indicated by the arrows, and Fig. 6 shows modified forms of holders in engagement with a trimming or mount for a brass bedstead.

The machine comprises a longitudinal I-beam 10 supported on a pair of brackets or standards 11—11 and at the head end of this I-beam I provide a casting 12 supplied with a pair of alined bearings 13 and 14 in which a shaft 15 is adapted to rotate, the shaft having a loose belt-driven pulley 16 which may be operatively-connected to the shaft by a clutch mechanism 17 operated by a bell-crank lever 18 fulcrumed at 19, one arm of the lever being disposed below an operating cam 20 on a short transverse shaft 21 equipped on the front side of the machine with a turning handle 22. Also mounted on this shaft 15 is a hand wheel 23 and a cylindrical electrically-conducting terminal 24 bearing on the outer face of which is a pair of brushes or contacts 25 connected to an insulated wire or cable 26, the brushes being insulated from the I-beam 10 by a strip 27 of fiber or the like, as is clearly indicated. This terminal 24 has an axial conical-shaped hole 28 (Fig. 3) which receives the correspondingly-shaped shank 29 of a tube or similar holder or center 30 conically recessed on its outer face at 31 and supplied with a forwardly-projecting pin or extension 32, as is shown in Fig. 2. It should, therefore, be apparent that the shaft 15 may be rotated either by power through the pulley 16 and the clutch mechanism, or by hand by means of the wheel 23, and that the rotation of this shaft is transmitted to the terminal 24 and the tube holder 30.

Slidably mounted on the top of the I-beam 10 is a tail stock casting 33 having at its top an elongated enlargement 34 supplied with a cylindrical cavity 35 coaxial with the shaft 15 and the parts carried thereby, this cavity receiving a coil expansion spring 36 which at one end abuts against the inner

wall of the cavity and at the other end bears against a member 37 slidable in the recess and supplied at its outer end with a cylindrical electrical terminal 38, substantially like the one characterized 24, this terminal also having a conical hole 39 receiving the conical shank 40 of a holder 41 like the holder 30, including the feature of the pin or extension 32. Insulatingly mounted on the casting 33 I provide a block 42 having a pair of electrical brushes or contacts 43 bearing on the cylindrical surface of the terminal 38, the block being provided on the back side of the machine with a spring-pressed contact 44 pressed against the outer plane face of a conducting bar 45 mounted on the back of the I-beam 10 and insulated therefrom, as is indicated. To conduct current to this bar I provide the insulated wire or cable 46, connected to the bar in any suitable manner at 47 or any other convenient point.

A shaft 48 is rotatably mounted in the pair of transverse alined bearings 49 on the casting 33, the shaft between these bearings having fixed thereto a pinion 50, the teeth of which mesh with those of a longitudinal rack 51 mounted on the I-beam 10 between its upstanding flanges. I fix to the end of the front bearing 49 and concentrically with the shaft 48 a stationary ratchet wheel 52, and on the shaft 48, rigid therewith, is an upwardly-extended arm 53. A short shaft or pin 54 is rotatable in a hole or bearing in the outer end of the arm 53, this pin having fixed to its inner end and overlapping the teeth of ratchet 52 a pawl 55 adapted to coact with the teeth. Through the other end of this pin or shaft I pass a cotter pin 56 and connect the eye thereof by a coil contractile spring 60 to the hub 57 of a rotary member 58 supplied with a plurality of handles 59, thus hub being loosely mounted on the shaft 48. This hub 57 is slotted at 61 to permit the arm 53 to extend therethrough, the slot being slightly wider than the arm, whereby the hub is permitted to have a limited rocking movement relative to the shaft 48 and the arm 53 without moving them. Secured to the inner end of its hub by means of screws 62 is a round plate or disk 63 having a notch 64 which permits the pawl 55 to normally engage the teeth 52 of the ratchet, but if the hub and handles 59 are turned, which turning is permitted by the width of the slot, relative to the shaft and arm 53 so that the pawl 55 no longer resides in the notch, then the pawl will be freed from the ratchet and backward movement of the same will be permitted, it being understood that the pawl is of sufficient width to overlap not only the ratchet 52 but also the notched plate 63, as is clearly indicated in Fig. 4. Owing to the contraction 65 of the spring 60 which acts to force the pawl

inwardly to engage the teeth of the ratchet, it also swings the hub 57 and handles 59 into such position as to bring the notch 64 of the plate 63 beneath the pawl, which position of the parts of course allows the pawl to operate with the ratchet.

The operation of this machine is substantially as follows: Assuming that the tube 65 intended to form part of a brass bedstead, and having apertured pommels or gromets 66 in its opposite ends, is to be lacquered, the tube is applied to the holder or center 30 so that the pin or extension 32 extends through the hole of the pommel 66 and the tube is then held in horizontal position during the advance of the tail stock until the pin 32 of the tail holder 41 engages the pommel at the other end of the tube, the latter being now supported at its opposite ends by the two pairs of pins. Further advance of the tail stock, due to the rotation of the member 58 by its handle 59, brings the tapered or conical faces 31 of the two holders 30 and 41 into effective engagement with the ends of the tube, and the tail stock is advanced sufficiently to put the spring 36 under some compression. During this forward travel of the tail stock the rotary turning of the hub 57 is transmitted to the shaft 48, gear 50, and tail stock casting by the rear wall of the recess 61 striking the arm 53, the pawl 55 riding idly over the inclined ratchet teeth, as will be readily understood. As soon as the operator releases the handles 59 the spring 60 is unable to force the tail stock rearwardly, because the pawl 55, by engagement with one of the teeth of the ratchet 52, prevents turning of the gear 50. The operator now closes an electrical switch 67 at the head end of the machine which controls the primary coil of an electric transformer through the wire connections 68, the secondary of such transformer sending its current through the wires 26 and 46 to the brushes 25 and 43 and terminals 24 and 38, from which it traverses and heats the tube. After the tube has been raised to the proper temperature, which takes but a very few seconds, the operator applies superposed or overlying coats of lacquer by means of a brush, the turning of the tube, in order that the entire surface may be covered, being accomplished by the manual rotation of the handle 23, the turning of which of course rotates the tube and terminals. If the part being lacquered has a mount or trimming 69, it may be desirable, instead of coating the same by stroking the brush longitudinally as is feasible in a tube of uniform diameter, to rotate the tube by power derived through the pulley 16, the lacquer being applied to the mount or trimming during such comparatively rapid rotation. To remove the finished tube it is simply necessary for

the operator to turn the handles 59 in the opposite direction, the initial movement of the hub of the handle acting to turn the disk 63 so as to lift the pawl 55 out of the notch 64 and away from the teeth of the ratchet 65, whereupon further turning of the handles retracts the tail stock. A comparatively slight backward movement of this tail stock frees the tube from the hold-
ers or centers 30 and 41 so that it is supported through its pommels on the pair of pins 32, which position of the tube permits the operator to grasp one or more of its ends internally by any suitable appliance without injuring its polished finished surface. Further backward movement of the tail stock frees the tube entirely so that it can be readily lifted out.

The holders 30 and 41, as will be readily understood, are easily detachable and removable from the terminals 24 and 38, and in order that this single form of machine may be used for lacquering the various parts of a bedstead, I keep a supply of holders or centers adapted to fit such parts, and in Fig. 6 I have shown a pair of holders or centers 70 and 71 having conical or tapered heads of different diameters adapted to directly fit in the opposite ends of a hollow mount or trimming 72, the use of which holders or centers enables me to obtain a sufficient electrical contact with the ends of the trimming or mount by forcing the holders toward one another.

Whereas herein I have set forth in detail the preferred embodiment of the invention, it is to be understood that the invention is susceptible of a variety of embodiments, and that it is not limited and restricted to the precise structural features herein set out.

I claim:

1. In a lacquering machine, the combination of a base, a pair of holders mounted thereon and adapted to support the piece 45 to be lacquered between them, each of said holders having a concave face and a central pin or extension thereon adapted to engage and enter the end of the piece held thereby, means for bodily adjusting one of said hold-
ers on said base toward and from the other, spring means normally urging one of said holders toward the end of the piece engaged thereby, means for electrically heating the piece to be lacquered while held by said 50 55 holders, and means for effecting rotation of the piece to be lacquered during the heating thereof, substantially as described.

2. In a lacquering machine, the combination of a base, a pair of holders mounted 60 thereon and adapted to support at its ends the piece to be lacquered, one of said holders being bodily movable on said base toward and from the other, mechanism, including a handle, for moving said last-named holder toward its companion holder, automatically acting detent mechanism to prevent backward movement of said movable holder in any of its adjusted positions, detent releasing means operated by a backward movement of said handle for permitting backward travel of said movable holder, means for effecting rotation of the piece to be lacquered while engaged by said holders, and 65 70 75 means for passing an electrical heating current through the piece to be lacquered while engaged by said holders, substantially as described.

WILLIAM WRIGHT VINCENT.
